(57) **CLAIM**

The ornamental design for a bottle, as shown and described.

DESCRIPTION

FIG. 1 is front and bottom perspective view of a bottle that has the design.

FIG. 2 is a front and top perspective view of the bottle.

FIG. 3 is a front elevation view of the bottle, the rear elevation view being a mirror image except for the threaded pour spout portion of the bottle.

FIG. 4 is a left-side elevation of the bottle. There is nothing on the right side of the bottle not seen in the other views.

FIG. 5 is a bottom plan view of the bottle; and,

FIG. 6 is a top plan view of the bottle.

1 Claim, 5 Drawing Sheets
